UNITED STATES PATENT OFFICE.

ALFRED W. ROOVERS, OF BROOKLYN, NEW YORK.

DESIGN FOR A STRENGTH OR POWER TESTING MACHINE CASE.

SPECIFICATION forming part of Design No. 19,221, dated July 23, 1889.

Application filed June 14, 1889. Serial No. 314,302. Term of patent 7 years.

To all whom it may concern:

Be it known that I, ALFRED W. ROOVERS, a citizen of the United States, residing at Brooklyn, in the county of Kings and State 5 of New York, have invented and produced a new and original Design for Strength or Power Testing Machine Cases, of which the following is a specification, reference being had to the accompanying drawing.

10 The drawing is a general view of my design.

The leading feature of my design resides in the base portion of the case; and it consists, broadly, of an irregular outline or contour, here representing the stump of a tree 15 and an animal mounted on the base.

Referring by letter to the drawing, A is an upright post or part of the case.

B is a drum or shell for mechanism. This shell B may be ornamented on its outer rim 20 or surface by embossed or raised figures, and an eagle C is mounted on the top of the shell.

The lower portion of the post A terminates in an irregular mass D, here representing the stump of a tree. This irregular mass is 25 mounted on a suitable base F, here indicating a rectangular form. An animal E is represented as climbing or mounted on one side of the irregular mass.

What I claim is—

30 A design for power-testing-machine cases, as herein described and shown.

ALFRED W. ROOVERS.
